Thorpe & Leonard,
his Attorney.

UNITED STATES PATENT OFFICE.

WARD T. BARKER, OF KANSAS CITY, MISSOURI.

OIL BURNER.

Application filed August 29, 1921. Serial No. 496,376.

To all whom it may concern:

Be it known that I, WARD T. BARKER, a citizen of the United States, residing at Kansas City, in the county of Jackson and State of Missouri, have invented a certain new and useful Improvement in Oil Burners, of which the following is a complete specification.

The present invention relates to oil burners for furnaces, and one of the principal objects in view is to provide an improved type of burner making use of a steam spray in conjunction with the oil discharge to insure the effective breaking up and vaporizing of the oil at the discharge point of the burner. Accordingly, I have devised an improved burner of this character in which a steam jet is provided at a location immediately adjacent to the oil discharge port, and of a size ample to answer all the requirements of said oil discharge port.

In this connection it is also sought to provide an improved adjusting means for regulating the size of the respective oil and steam discharge ports, and operating to simultaneously regulate the same according to requirements, while preserving the relative size between the two ports.

In carrying out this adjustable feature of the improved burner, I provide separate oil and steam chambers having a rotatable member forming the partition between the chambers, and so arranged that the oil and steam discharge ports are regulated in size by the mere rotation of said partition element.

With these and various minor objects in view, the invention will now be described by reference to the accompanying drawing, illustrating one form of construction which I have devised for embodying the proposed improvements, after which the novel features therein will be particularly set forth and claimed.

In the drawing—

Figure 1 is a side elevation, illustrating a burner construction embodying the improvements;

Figure 2 is an enlarged face view of the burner proper;

Figure 3 is a vertical sectional view of the same;

Figures 4 and 5 are transverse sections, taken on the lines IV—IV and V—V, respectively, of Figure 3;

Figure 6 is a detail section taken on the line VI—VI of Figure 5;

Figure 7 is a perspective view showing the rotatable partition element which separates the oil and steam discharge chambers; and

Figure 8 is a vertical sectional view, showing the by-pass connections between the oil and steam lines leading to the burner.

Referring now to the drawing in detail, this shows the improved burner device as comprising substantially similar inlet connections 10 and 12, the former being fitted with an oil supply pipe 14, and the latter having a steam supply pipe 15, as shown in Figure 1. Joining the inlet connections 10 and 12 is a bolt 16, which serves as a common axis of adjustment for an oil chamber element 17, a steam chamber element 18, and also a rotary partition element 19 interposed between the elements 17 and 18 and thereby serving to separate the oil discharge chamber 20 from the steam discharge chamber 21, as will be found clearly illustrated in Figure 3. Each inlet connection is provided with an undercut passage 23, one of which passages communicates with the chamber 20 through an arcuate opening 24 in the element 17, while the other passage 23 communicates with the chamber 21 through a similar arcuate opening 24 in the element 18. Each of the elements 17 and 18 is provided with a clamping screw 25 passing through the corresponding opening 24 and into engagement with the corresponding inlet connection 10 or 12, whereby either of the elements 17 or 18 may be rotated about the axis of the bolt 16 and clamped in any position of adjustment, for a purpose hereinafter explained.

At the front of the burner are provided a steam jet opening 30 communicating with the steam discharge chamber 21, and also an oil discharge port 31 communicating with the interior of the oil chamber 20. These discharge ports or openings are produced by cutting the contacting edges of the partition element 19 with the chamber elements 17 and 18 along spiral lines extending in

opposite directions. In the case of the elements 17 and 19 for producing the discharge opening 31, the spiral cut starts with a shoulder 32 on the element 17 and terminates with a shoulder 33 on the partition element 19, so that the discharge opening 31 is produced by relation rotation of the elements 17 and 19, thereby separating the shoulders 32 and 33, and thereby also regulating the size of the oil discharge opening 31, according to the extent of separation of said shoulders 32 and 33. In the case of the steam discharge opening 30, the spiral cut begins with a shoulder 34 on the element 18 and proceeds in a spirally opposite direction (as regards the first mentioned spiral cut), and terminates in a similar shoulder 35 formed on the element 19, so that the opening 30 is formed, and the size thereof regulated, in the same manner as the oil discharge opening 31. From this it will be seen that after the relative size of the openings 30 and 31 is initially determined, the rotary adjustment of the partition element 19 will serve to simultaneously regulate the size of both of said openings, increasing or diminishing the same, according to requirements.

Associated with the pipe connections 14 and 15 is a by-pass arrangement, whereby oil received from a lower level than that of the steam supply may be by-passed around the steam so as to feed the oil to the top chamber of the burner and allow the steam 30 to be passed to the lower chamber 21 of the burner. Referring to Figures 1 and 8 of the drawing, it will be noted that the pipe 14 communicates with a passage 40 of a by-pass head 41, while the steam pipe 15 35 communicates with a passage 42 in said head member 41 (see Figure 8). Attached to the outer ends of the head member 41 is a pair of nipples 43 the upper one of which is engaged by an L-casting 44, the lower nipple 43 being clamped in communication with a crosshead element 45 engaged by the opposite arms of a yoke member 46 the head of which is provided with a clamping screw 47 engaging the L-casting 44 and 40 operating the same to securely clamp all the parts of the by-pass structure together as shown. The cross head member 45 communicates with a pipe 48 provided with a valve, (not shown) for regulating the flow 45 of oil to the passage 40 and thence to the burner. The L-casting member 44 communicates with a steam pipe 49 fitted with a valve 50 for regulating the supply of steam to the passage 42 and thence to the burner. A valve 51 is adapted to allow opening of the passage 40 into communication with the passage 42, whereby a jet of steam may be discharged through the oil chamber 20, to blow out and thoroughly 55 clean the latter as often as may be desired.

It will thus be apparent that I have devised a simple, practical and efficient burner construction for fulfilling the desired objects of the invention. The size of the discharge ports 30 and 31 is initially adjusted, by rotating the parts 17 and 18 about the axis of the bolt 16, and clamping the same by means of the clamping screws 25 for setting the shoulders 32 and 34 at the proper relative locations for determining the correct relative size of the oil and steam ports 31 and 30, the latter of which should be slightly greater than the former in order that the entire oil jet will be subjected to the heating and atomizing effect of the steam. After the initial adjustment of the shoulders 32 and 34 has been obtained for adapting the burner to the grade of oil to be used, the size of the jets may be regulated, for either increasing or diminishing the size of the ports, by rotating the partition element 19. The described assembly of parts forms a tight burner structure, in which all the parts fit closely and evenly together and at the same time allow all the adjustments provided for without any chance of any seams or openings occurring except at the jet orifices 30 and 31.

It will be understood that the by-pass construction is designed to be located outside the furnace, and enables the oil and steam lines (usually arranged with the steam line above) to be crossed in order that the steam may be supplied to the lower chamber of the burner as required for obtaining the correct burner action. The by-pass head construction also enables a pre-heating action to be exerted upon the oil flow, and the position of the valve 51 allows a blast of steam to be blown through the oil connection and discharge chamber 20 for effectively blowing out and cleaning the same.

While I have illustrated and described what I now regard as the preferred form of construction for embodying the proposed improvements, I desire to reserve the right to make such changes or modifications as may fairly fall within the scope of the pending claims.

What I claim is—

1. An oil burner comprising oil and steam inlet connections, and relatively rotatable coaxial elements providing separate adjacent outlet ports in communication, respectively, with said oil and steam inlet connection, said ports comprising slots extending angularly with respect to the axis of said rotatable elements.
2. An oil burner comprising an oil supply connection, and relatively rotatable coaxial elements providing an oil chamber, said elements being provided with an oil discharge port regulated in size by the relative rotative movement of said elements;

said port being formed as a slot extending angularly with respect to the axis of said rotatable elements.

3. An oil burner comprising a device providing oil and steam chambers, and a rotatable disc element forming a partition between said chambers, said chambers being provided with adjacent oil and steam discharge ports regulated in size by rotation of 10 said element.

4. An oil burner comprising a device providing oil and steam chambers, a rotatable disc element forming a partition between said chambers, said chambers being provided 15 with adjacent oil and steam discharge ports regulated in size by rotation of said element, and means permitting initial relative size adjustment of said ports.

5. An oil burner comprising oil and steam inlet connections, relatively rotatable coaxial members forming steam and oil chambers in communication, respectively, with said steam and oil connections, and a rotatable partition element between said members, 20 said members and partition element being formed with separate spaced discharge ports from said chambers simultaneously regu-

lated in size by rotation of said partition element, the relative size of said ports being further adjustable by relative movement of 30 said members.

6. An oil burner comprising oil and steam inlet connections, relatively rotatable coaxial cylindrical members forming steam and oil chambers in communication, respectively, 35 with said steam and oil connections, and a cylindrical partition element rotatably mounted between said members, the lines of engagement between said partition element and said members extending in 40 spirally opposite directions and having a shoulder connecting the ends of each spiral edge of said element and members, thereby forming discharge ports between each pair of shoulders when separated by partial rotation of said partition element, the size of said ports being regulated by the degree of rotative movement of said element, the relative size of said ports being further adjustable by relative rotative movement of 45 50 said members.

In witness whereof I hereunto affix my signature.

WARD T. BARKER.
